(57) **CLAIM**

(21) Appl. No.: **29/257,145**

The ornamental design for a radiator grille for vehicle, as shown and described.

(22) Filed: **Mar. 30, 2006**

DESCRIPTION

(30) **Foreign Application Priority Data**

Aug. 31, 2005 (JP) D2005-25140

(51) **LOC (8) Cl.** **12-16**

FIG. 1 is a perspective view of a radiator grille for vehicle;

(52) **U.S. Cl.** **D12/163**

FIG. 2 is a front view thereof;

(58) **Field of Classification Search** D12/163,

FIG. 3 is a rear view thereof;

D12/171, 90-92, 216, 169, 196; 180/68.1,
180/68.6; 296/193.11; 293/102, 113, 115

FIG. 4 is a top plan view thereof;

See application file for complete search history.

FIG. 5 is a bottom view thereof;

(56) **References Cited**

FIG. 6 is a right side view thereof;

U.S. PATENT DOCUMENTS

FIG. 7 is an enlarged sectional view thereof taken along line
7—7;

D514,480 S * 2/2006 Yamaji et al. D12/163

FIG. 8 is an enlarged sectional view thereof taken along line
8—8;

D519,890 S * 5/2006 Sakae D12/163

FIG. 9 is an enlarged sectional view thereof taken along line
9—9; and,

D525,177 S * 7/2006 Kitazumi D12/163

FIG. 10 is an enlarged sectional view thereof taken along
line 10—10.
